SELECTIVE CONTROLLING DEVICE FOR
ELECTRICALLY OPERATED BROCADE
LOOMS

Kinsaku Nakanishi, Hakata, Fukuoka, Japan

Application February 6, 1934, Serial No. 710,002
In Japan February 13, 1933

4 Claims. (Cl. 139—319)

This invention relates to improvements in selective controlling devices for electrically operated brocade looms, card cutting machines and other similar purposes, and its principal object 5 is to provide a selective mechanism for operating brocade looms and card cutting machines and the like whereby the successive selective operations may be completed during the actuation of the operating elements of the machinery so 10 that the successive weaving or punching operations may be effected immediately without wasting idle time until the operating elements have completed their operations and have been moved to the newly selected positions, thereby considerably increasing the operating efficiency.

For a better understanding of my invention reference may be had to the accompanying drawings in which Fig. 1 is a perspective view illustrating an arrangement for selectively operating the hooks of a brocade loom photo-electrically; Fig. 2 is an enlarged detail view of a selective controlling member for the hooks of the device shown in Fig. 1; Figs. 3 and 4 are side elevations of its modifications respectively; and Figs. 20 25 to 8 are side elevations of modified arrangements of a portion of the device shown in Fig. 4.

Referring now to Fig. 1 of the accompanying drawings, 1 represents a sliding board bearing an original picture of a design; 2 is a light source; 3 is a lens; 4 is a prism; 5 is a photo-electric cell; 6 is a shutter and 7 is its driving motor.

These elements are so arranged as to project the light from the source 2 onto the picture on the sliding board 1 as a light spot and to project its reflected light into the photo-electric cell as shown in the drawings. An amplifier 8 is connected in the output circuit of the photo-electric cell and its output current is led to the operating coil of a relay 9 to close its contact 40 10 or 11 in response to the shading of different elements of the original picture. 12 designates a change-over switch which is suitably changed as the picture is positive or negative. The switch is manually set at the start of weaving operation 45 and kept at the position throughout the operation. 13 represents a suitable source such, for instance, as a battery which is provided for energizing the bus-bar 15 through a series adjustable resistor 14, the contact of relay 9 and switch 12, and thence the actuating coil of a selecting 50 electromagnet of rotary type.

The present selecting electromagnet is supported on a shifting bracket 17 mounted on a feeding screw shaft 16 and comprises a plurality of electromagnets such as for instance, four elec-

tromagnets mounted on a supporting frame 19 which is keyed to the revolving shaft 18. All electromagnets are arranged to be energized in series or in parallel through the brushes 21 secured to the supporting frame 17 and the lead 5 wires 22. A roller 24 is attached to one end of its armature and when the armature 23 is attracted the roller 24 pushes one which comes in opposite position thereto out of a number of latches 25 and 25' to be selected which correspond in number to those of the picture elements and are arranged at opposite sides of the selecting electromagnet alternately as will clearly be seen in Fig. 2, to displace the latch to the position shown by dotted lines. 28 is a biasing 15 spring of the armature 23 and 29 is a biasing spring for the latch 25 to be selected.

One end of the selecting lever 27 supported at the pivot 26 is engaged with the latch 25 to be selected and is moved to the position shown by 20 the dotted lines by means of a bias spring 30 when released. A selecting lever 27 is pressed on one side by the selecting rod 32 by means of a spring 31 and also it is adapted to be operated by a restoring rod 60 when projected. The re- 25 storing rod 60 is normally biased to an inoperative position as shown in the drawings by means of the spring 61 and a cam 64 mounted on a side shaft 63 is associated with the other end of the restoring rod directly or through a lever 62. Thus 30 all of the latches 25 and 25' may be restored to a position ready to be selected, as shown by the full lines, periodically as soon as the knife edge 34 is lifted to make it possible to start the next scanning operation and complete its selective 35 control without delay while the knife edge 34 is being lifted and the brocade is being woven. 35 is a string suspended from the lower end of the hook 33; 36 is a harness head connected to the string; 37 is a hemp thread; 38 is a harness 40 provided with a thread opening 40 for passing through a warp thread 39 and 41 designates a dead weight. 42 is a winding drum; 65 is a shuttle carrying a weft and 43 is a reed for beating in the weft.

The driving means for synchronizing the movements of selecting electromagnets and sliding board 1 will be explained in the following:— In the example shown in Fig. 1, an operating shaft 47 is driven by a motor 44 through bevel gears 45 and 46 and the motion is transmitted to the screw shaft 16 through either one of the upper and lower bevel gears 48 and 49 mounted on the shaft 47 and a bevel gear 50 mounted on the screw shaft 16. A side shaft 18 is revolved 55

through gears 51 and 52. The driving shaft 56 of the cam 55 is also revolved through a worm 53 and a worm wheel 54. The sliding board 1 is normally put in contact with the cam 55 by means of weight 57. 58 is a handle provided for operating either one of the bevel gears 48 and 49 with the shaft 47 to shift the sliding board 1 and the electromagnet back and forth. The sliding board 1 is provided with a driving mechanism 59 for shifting the board by one pitch along transverse direction at each stroke of its longitudinal direction.

With the above mentioned device I will explain the manner by which a brocade corresponding to the original picture is woven by putting the picture of a certain design on the sliding board 1 and illuminating the light source 2. Then the motor 44 is started and the screw shaft 16, the side shaft 18 and the cam 55 are driven through the gear train as above mentioned and the supporting bracket 17 of the electromagnet and the sliding board 1 are shifted in synchronism. Thus the selecting electromagnet 20 is simultaneously rotated by the side shaft 18.

Then, one latch 25 to be selected which corresponds to the scanned picture element of the original picture on the sliding board 1, is always brought to face one of the rotary electromagnets and is controlled by the roller 24 on its armature 23. If a bright spot of the original picture is being scanned and the contact 11 of the relay 9 is closed with the photo-electric current the bus-bar 15 will be energized from the source 13 through the resistance 14, the relay contact 11 and the switch 12 when the bright element is scanned and thus energizes the electromagnet 20 through the brush 21. Accordingly, the armature 23 will be attracted as shown by the dotted lines of Fig. 2 to rotate the latch 25 to be selected counter-clockwise around its pivot, thereby releasing the selecting element 27 and displacing the same to the dotted line position by means of a spring 30. Thus, the selecting rod 32 is pushed to the right and the hook 33 will assume the dotted line position ready to engage with the knife edge 34. As for the latch 25 to be selected which corresponds to the dark element of the original picture, since the relay 9 closes its contact 10 and opens the contacts 11 for such a dark current said latch will remain to the full line position and its hook 33 will assume the full line position disengaged from the knife edge 34. Thus, at the end of one stroke of the sliding board 1, all of the latches 25 to be selected are arranged so that one line corresponding to one scanning line of the original picture may be drawn by a weft. Accordingly, if the knife edge 34 is lifted to pull up the warps 38 belonging to the hooks 33 engaging with the knife edge and a weft is threaded therethrough by means of a shuttle 65 after one stroke of the sliding board 1 or one line scanning is completed, a textile bearing a design corresponding to the original picture will be produced.

As above mentioned immediately after the knife edge 34 is lifted the lever 62 is rotated counter-clockwise by the cam 64 and the restoring rod 66 is pushed to the left at its one end so that all of the selecting elements 27 are simultaneously pushed back to a position ready for the selective operation as shown by the full lines and the successive scanning or selecting operations may be started immediately. Thus, at the beginning of the weaving operation of the loom members 43 and 65, the next selection is already

stated so that the waste of time which occurs in machines heretofore used in which the selecting operation is started after the knife edge 34 has been lowered, is avoided and high-speed operation is made possible, thereby considerably increasing the efficiency.

Further, since a small number of electromagnets is rotatably combined and these magnets are shifted in synchronism with the scanning operation of the original picture, it has characteristics that the spacing between the latches 25 equal to the number of the picture elements included in one scanning line of the original picture, is reduced, thereby affording a compact structure as a whole. If the latches 25 and 25' to be selected are arranged alternately in two rows as specially shown in Fig. 2, its volume will be considerably reduced.

In Fig. 3, a synchronous electromagnetic device adapted to move in synchronism with the scanning operation of the original picture is associated with the latches 25 to be selected which are similar to those shown in Figs. 1 and 2. Since the same reference characters are used to designate similar parts in these figures, its operation will easily be understood from the explanation of Figs. 1 and 2.

Fig. 4 illustrates an embodiment of this invention as applied to an arrangement in which instead of the selecting electromagnet of a synchronous rotary shifting type as shown in Figs. 1 and 2, a number of fixed electromagnets 20 corresponding with each picture element of the original picture are arranged and the energization is selectively controlled through a distributor comprising the same number of contacts and a co-operative brush having a synchronous relation with the scanning operation of the original picture. The selecting element 27 is engaged with the latch 25 to be selected, which is attached to the fixed electromagnet 20. Figs. 5 to 8 designate its modifications and the arrangements are similar to that shown in Fig. 2. Accordingly, their detailed explanations are omitted by only designating the similar parts with the same reference characters as in Fig. 2.

In any of the above arrangements, the selecting elements 27 are returned to the full line positions ready for the selective operation by means of the restoring rod 66 as soon as the lifting movement is started irrespective of the lifting operation of the hooks 33 and the successive selection is immediately started so that the latches may assume the next selected positions by the time the hooks 33 are lowered. Thus, this invention has advantages that the weaving operation may be completed quickly and accurately without wasting double time as occurs in heretofore used looms, in which the weaving operation should be effected after the weft has been threaded and the next selective control has been completed.

The arrangement of the optical system 2, 3, 6 and 4 may be selected suitably and is not necessarily limited to that shown in the drawings. It is enough if the concentrated light may be projected on the original picture. While the reflected light ray is shown to be projected into the photo-electric cell 5 the light ray which has passed thru the picture may, of course, be used. If a sufficient current can be derived from the photo-electric cell 5 and in other similar cases, the amplifier 8 and/or the relay 9 may be dispensed with. The original picture may be divided into several sections and a photo-electric cell and an electromagnet are associated with

each section respectively to scan the sections simultaneously, thereby increasing its operating efficiency considerably.

What I claim as new and desire to secure by Letters Patent of the United States, is:

- 5 1. A selective controlling device for electrically operated brocade looms, comprising means for generating a photo-electric current corresponding to an original picture of a certain design, electromagnets energized with said photo-electric current, latches controlled by said electromagnets, selecting elements normally caught by said latches respectively, said elements being put in contact with selecting rods for moving hooks 10 to positions ready to be engaged by a lifting knife edge, and restoring rods associated with said selecting elements periodically with a predetermined relation to the scanning operation of the original picture.
- 20 2. A selective controlling device used for electrically operated brocade looms, comprising means for generating a photo-electric current corresponding to an original picture of a suitable design, a plurality of electromagnets mounted 25 rotatably on a shifting bracket moving in synchronism with the scanning operation of the original picture and adapted to be energized with said photo-electric current, latches arranged along the path of said electromagnets to be operated thereby in number corresponding to the number of the picture elements scanned on the original picture, selecting elements normally caught by said latches and adapted to push selecting rods for moving harness hooks to positions ready to be 30 engaged by a lifting knife edge, and restoring rods associated with said selecting elements for pushing said selecting elements back to the normal positions as soon as said hooks are lifted by said lifting knife edge.
- 35 3. A selective controlling device used for electric brocade looms, comprising means for generating a photo-electric current which varies responsively to the shading of the scanned elements

of an original design picture, an electromagnet adapted to be shifted in synchronism with the scanning operation of the original picture, latches arranged alternately in two rows and in number corresponding to the number of elements scanned on said original picture so as to be operated by said electromagnet shifting along the central passage between the two rows of latches, selecting elements normally caught by said latches, selecting rods pressed against said selecting elements respectively for moving hooks to the position ready to be engaged by a lifting knife edge, and restoring rods associated with said selecting elements to be projected periodically so as to restore said selecting elements to their normal positions 15 as soon as said lifting knife edge is lifted.

4. A selective controlling device used for electric brocade looms, comprising means for generating a photo-electric current which varies responsively to the shading of the scanned elements of an original design picture a number of fixed electromagnets corresponding in number to the picture elements scanned on the original picture, a distributor comprising contacts equal in number to said magnets and a co-operating movable brush adapted to be worked in synchronous relation to the scanning operation of the original picture so as to energize one of said electromagnets corresponding to the picture element scanned with said photo-electric current there- 30 through, selecting elements normally held by latches to be operated by said electromagnets, selecting rods pressed against said selecting elements for selectively operating harness hooks to positions ready to be engaged with a lifting knife 35 edge, and a restoring rod associated with said selecting elements so that the latter may be pushed back to their normal positions at a period bearing a predetermined relation with the scanning operation of said original picture and the 40 movement of said lifting knife edge.

KINSAKU NAKANISHI.
